ENGINE STARTER APPARATUS

Samuel Gilbert, Cedar Grove, N. J., assignor to
 Bendix Aviation Corporation, Teterboro, N. J.,
 a corporation of Delaware

Application November 26, 1946, Serial No. 712,465

2 Claims. (Cl. 123—179)

1

The invention hereof relates to engine starter apparatus, and particularly to novel elements and combination thereof adapting an engine, not previously so constructed, for receiving a starter.

Among the objects of the invention are to overcome objections to ordinary hand cranking, such as difficult crank turning, and danger of injury to the operator, and to effect these results by novel effective means.

Another object is to provide novel adapter means providing for mounting a starter relative to an engine, without appreciably altering the engine exteriorly, or within the engine, its hood, or any other part or associated structure.

Another object is to provide novel jaw means for extending the position of engagement of one of the engine or starter jaws relative to the other.

Another object is to provide novel means whereby an engine, which is normally started by a hand crank, may be very quickly converted to an engine having a starter at its front or normally non-load end.

Another object, in association with the above-mentioned features, is to provide means for operating the starter, which is mounted on the adapter for direct mounting on the adapter with the starter, so that no appreciable alteration of the engine or associated parts is necessary to receive the operating means.

Another object is to associate the features of the above given objects with torque limiting means for preventing injury to the starter from excessive load or backfire at its output or jaw end, and also from excessive force applied internally of the starter irrespective of such load.

Another object is to provide starter apparatus of the above-indicated character which is simple and durable in construction, economical to manufacture and effective in its operation.

These and other objects and features of the invention are pointed out in the following description in terms of the embodiment thereof which is shown in the accompanying drawings. It is to be understood, however, that the drawings are for the purpose of illustration only, and are not designed as a definition of the limits of the invention, reference being had to the appended claims for this purpose.

In the drawings:

Figure 1 is a broken top view, partially in section and partially in elevation, of a structure, including portions of an engine, an adapter, and a starter, embodying the invention;

Figure 2 is a front elevation, on a reduced scale, 55

2

of the structure of Figure 1 taken from the left thereof; and

Figure 3 is a view in side elevation of the structure of Figure 1 on the scale of Figure 2.

Referring to the drawings, an engine shaft 10 is shown as including a stub end 12, Figure 1, of smaller diameter having usual means, such as a press fit pin 14, which holds a one-piece member 16 comprising a pulley 18, as for a fan belt, and an engine jaw or member 20.

Prior to this invention, a member similar to the member 16 had a pulley like the pulley 18, but, instead of the jaw 20, was provided with a usual bayonet type connector portion for receiving one end of a hand crank.

Adapter means 22 is, in this instance, in the form of a one-piece cast bracket including an engine mounting end portion 24 having an engine supporting lower portion 26, see Figures 2 and 3, the latter portion of which takes the place of a former engine support. The portion 24 has an upper central rear portion 28 and other parts for the reception of studs by which the adapter 22 is secured to the engine in the place of the former support.

A normally horizontal portion 32 of the adapter 22, which in this instance is in the form of a web or apron, extends forwardly from the portion 24 under a radiator 33, indicated in Figure 3 by broken lines. The side edges of the apron 32 converge from the plate 24 to an upright portion 34 including a rounded top 36, and having a central aperture through which extends a starter jaw member 38, and holes about the member 38 for receiving mounting bolts 40.

A starter 42 comprises a housing 44 including a baffle plate end portion 46 having a flange 48 secured to a flange 50 of a housing portion 52, as by bolts 40. The housing portion 52 is secured to a housing portion 56 having a partition 58, Figure 1, to which a cover 60 is secured, as by bolts 62. A flywheel or inertia member 64 is keyed to a shaft 66, having a pinion 68, and journaled in anti-friction bearings 70 mounted on the partition 58. A bell gear 72, journaled by anti-friction bearings 74 in a bearing support 76 of the partition 58 and engaging the pinion 68, has a pinion 78 engaging a rotatable internal gear 80 having a sun gear portion 82 journaled about a tubular sleeve 84, which extends through an end wall 86 of a barrel 88, and has a disc-like portion 90 in the barrel 88 for a purpose later pointed out.

Planet gears 92, engaging the sun gear 82 and a stationary orbital gear 94 of the housing portion

52, are journaled by anti-friction bearings 96 on trunnions 98 protruding from the barrel end wall 86.

A bevel gear 100, splined to the sleeve 84, engages a bevel gear 102, journaled by anti-friction bearings 104 in portions of the partition 58, which gear 102 is mounted on a shaft 108 having secured thereto, exteriorly of the housing 44, a member 110 adapted to secure a shaft 112, as by a usual hand crank bayonet type connection.

Means, such as an arm 114, extending laterally from the starter 42 and secured thereto as by studs 116, is provided with bearing means 118 spaced from the starter for the shaft 112.

The starter operating or hand cranking element or shaft 112 is provided with means 120, at its outer end, for receiving a hand crank 122 or other means.

A two-part torque limiting friction disc pack 124, including the disc 90, in the barrel 88, has 20 discs of one part splined to the barrel and to an axially stationary rotatable hollow nut 126, respectively, and discs of the other part connected to the barrel, and through the disc 90, to the bevel gear 100, respectively, all of the discs being adjusted relative to each other by springs 130 and a ring nut 132 screw threaded to the barrel therein.

A screw shaft 134 has long lead thread connection to the nut 126 therein, and a shoulder adapted to engage a shoulder of the nut, after predetermined axial movement relative thereto for rotation therewith.

The elongated starter jaw member 38 comprises a screw shaft securing length or shank portion 136 at one end having a spline connection 138 to the screw shaft 134, a jaw portion or member 140 at the other end for cooperation with the engine jaw 20, and a hollow or tubular body 142 of substantial length, or of sufficient length in this instance to cross the radiator 33, or other element, between the engine and the starter.

A mesh rod 144, having portions of different diameter providing a shoulder 146 for engagement with one end of the screw shaft 134, is pivotally connected at one end to a clevis at one end of a lever 148, which is connected to a rod 147, see Figure 2, journaled in the housing portion 56 and carrying a bell crank lever 149 exteriorly of the housing. A spring 151, coiled about the rod 147, acts oppositely against the housing and the lever 148 to bias the mesh rod 144 to the left, as seen in Figure 1. The mesh rod has its other end provided with a sliding seal 150 of washer-like character normally held against a web 152 of the body 142 by a spring 154 between the web and a shoulder in the screw shaft.

Openings 156 are provided in the starter jaw member 38 to provide access to a locking nut 160 at the other end of the mesh rod 144, which nut axially retains the member 38 in position.

Although the starter is not subject to oil from the engine, as in many former applications, it is sealed against the admission of moisture and other liquids by a ring seal 162 around the shank 136, which has rotative and axial sliding contact with the seal.

In operation, with the parts shown related as they are either when the engine is running or not running, if it is not running, and it is desired to start it, the crank 122, in this instance, is attached to the means 120 and turned to rotate the shaft 112. Rotation of the shaft 112 is transmitted, through the member 110 and the shaft 108, to the bevel gear 102, the bevel gear 100, the

sleeve 84, the disc 90, the pack 124, the barrel 88, the planet gears 92, the stationary orbital and rotatable sun gears 94 and 82, respectively, the rotatable internal gear 80, the pinion 78, the bell gear 72, the pinion 68 and the shaft 66 to the flywheel 64. If the force applied to the crank 122 and the shaft 112 is excessive to a degree likely to injure the starter parts, irrespective of starting the engine, the disc 90 slips. However, if no such excessive force is applied or when it ceases, turning of the bevel gear 102 by the proper force is continued until the flywheel 64 attains a predetermined speed sufficient to start the engine. At this point, the operator should ordinarily cease turning the crank 122, but whether he does or not, he should, at substantially the instant the flywheel attains its engine starting speed, operate the bell crank 149 to move the mesh rod 144 against the bias of the spring 151 to the right, as viewed in Figure 1. Such movement causes the shoulder 146 to move the screw shaft 134 and the jaw member 38 to the right through the intermediary of the spring 154, to engage the starter jaw member 38 to the engine jaw member 20, whereupon the stored energy of the flywheel 64 comes into play to turn the jaw members.

If the engine jaw member 20 imposes excessive torque, or the engine backfires, the resultant shock is absorbed by the portion of the pack 124 to the right of the disc 90.

As soon as the engine starts, the lever 149 should be released but if it is not released quickly, the engine jaw 20 will override the starter jaw 140 against the action of the spring 154 until release of the bell crank 149, whereupon the spring 151 will return the parts to the retracted or initial positions shown.

Although only one embodiment of the invention has been illustrated and described, various changes in the form and relative arrangements of the parts, which will appear to those skilled in the art, may be made without departing from the scope of the invention. Reference is, therefore, to be had to the appended claims for a definition of the limits of the invention.

What is claimed is:

1. In starter apparatus for an engine including a radiator and a shaft, said apparatus comprising a starter including a flywheel, a flywheel pinion, a rotatable internal gear having a sun gear, a bell gear engaging said pinion and having a pinion engaging said internal gear, a stationary orbital gear, a barrel, planet gears between said stationary orbital and sun gears, an axially stationary rotatable nut in said barrel, a bevel gear coaxial with said internal and orbital gears, a two-part torque limiting friction disc pack in said barrel having discs of one part splined to said barrel and said nut, respectively, and discs of the other part connected to said barrel and said bevel gear, respectively, a second bevel gear engaging said first bevel gear, mesh rod means, and a screw shaft having long lead thread connection to said nut therein, the combination of a one-piece engine-jaw member adapted for mounting on said engine shaft end, adapter means having an end portion adapted for mounting on the engine with an intermediate portion extending under the radiator and a starter mounting opposite end portion extending upwardly from said intermediate portion at a position beyond the radiator from the engine, a one-piece starter jaw member having its jaw means at one end and a shank at the other end splined to said screw shaft, said starter jaw member hav-

ing an elongated tubular body extending from said shank end under the radiator above said intermediate adapter portion to its jaw means at the other end for cooperation with the engine jaw member, said mesh rod means being operative for actuating said screw shaft to engage said starter jaw member to said engine jaw member, an arm carried by and extending from said starter and having bearing means spaced from the starter and a shaft in said bearing means having opposite end means adapted for bayonet connection to said second bevel gear and a hand crank, respectively.

2. In starter apparatus for an engine including a radiator and a shaft, said apparatus comprising a starter including a flywheel, a flywheel pinion, a rotatable internal gear having a sun gear, a bell gear engaging said pinion and having a pinion engaging said internal gear, a stationary orbital gear, a barrel, planet gears between said stationary and sun gears, an axially stationary rotatable nut in said barrel, a bevel gear coaxial with said internal and orbital gears, a two-part torque limiting friction disc pack in said barrel having discs of one part splined to said barrel and said nut, respectively, and discs of the other part connected to said barrel and said bevel gear, respectively, hand crank receiving means including a second bevel gear connected to said first bevel gear, mesh rod means, and a screw shaft

10
15

30

having long lead thread connection to said nut, the combination of an engine jaw member adapted for mounting on said engine shaft, adapter means having a portion adapted for mounting on the engine with portions extending under the radiator and a starter mounting portion at a position beyond the radiator from the engine, and a starter jaw member including a shank splined to said screw shaft and having an elongated body extending from said shank at one end under the radiator to its jaw means at the other end for cooperation with the engine jaw member, said mesh rod means being operative for actuating said screw shaft to engage said starter jaw member to said engine jaw member.
